UNITED STATES PATENT OFFICE

2,202,799

STENCILING APPARATUS

Albert S. Jackson and Clarence A. Heyne, Alton,
Ill., assignors to Owens-Illinois Glass Com-
pany, a corporation of Ohio

Application December 7, 1938, Serial No. 244,430

13. Claims. (Cl. 101—124)

The improved stenciling apparatus comprising the present invention is primarily adapted for use in applying a vitreous enamel composition or paint to the tapered shoulder portions of articles of glassware such as bottles or jars in the lettering or decorating thereof by a stenciling process.

The principal object of the invention is to provide a stenciling apparatus which will generally 10 simplify the setting up operations for bottles of different sizes or for bottles having tapered shoulder portions that differ in slope and which will also generally simplify and improve the operation of applying the vitreous enamel composition to 15 such articles, thus improving the quantity of the work performed as well as the quality and uniformity thereof and also lessening the labor or skill otherwise required in performing the same type of stenciling operations.

20 The invention is embodied in an apparatus of the type employing a reciprocable stencil screen capable of oscillatory movement relative to the article undergoing decoration together with a relatively stationary squeegee by means of which the 25 enamel composition is forced through the screen and onto the surface of the article undergoing decoration. A further object of the invention is to provide an apparatus of the character referred to in which there is incorporated an improved 30 means for varying the extent or amplitude of screen oscillation to accommodate bottles having varying characteristics.

Another object of the invention is to provide 35 an improved squeegee supporting assembly in which the squeegee is adjustable relative to the stencil screen and from which it is readily removable.

Other objects of the invention, not at this 40 time enumerated, will become readily apparent as the nature of the invention is better understood.

In the accompanying drawings:

Fig. 1 is a side elevational view of a stenciling apparatus constructed in accordance with the 45 principles of the present invention;

Fig. 2 is an enlarged detailed side elevational view, partly in section, of the apparatus proper;

Fig. 17 is a diagrammatic view similar to Fig. 16 with the screen in its other extreme position;

Fig. 18 is an end elevational view of a control 25 valve employed in connection with the invention;

Fig. 19 is a vertical sectional view taken through the valve of Fig. 18;

Fig. 20 is a fragmentary side elevational view, 30 partly in section, of an actuating valve employed in connection with the invention;

Fig. 21 is another fragmentary elevational view 35 of the actuating valve showing the valve plunger in a different position; and

Fig. 22 is a sectional view taken substantially 40 along the line 22—22 of Fig. 19;

BRIEF DESCRIPTION

Briefly, referring to Fig. 1, the apparatus is 40 semi-automatic in operation and involves in its general organization a wheeled frame or carrier 30 including a table portion 31 upon which are mounted the various decorating instrumentalities proper. A tiltable bottle supporting assembly 45 32, also mounted on the table portion 31, includes a base chuck 33 and a head chuck 34 adapted to support therebetween a bottle B or other article to be decorated. Means is provided for adjusting the inclination of the bottle supporting assembly 32 and for clamping the same in any desired adjusted position in order that the tapered shoulder portion of the bottle B may be brought into tangential rolling line contact with the underneath surface of a horizontally oscillatable 50 stencil screen S forming a part of a stencil screen assembly 35.

The head chuck 34 is movable toward and away from the base chuck 33, such movement being effected by a piston motor 36 which is ac- 55

tuated by a control valve 37 (Fig. 4). Upon initial depression of a foot treadle 38, the control valve 37 is actuated and the head chuck 34 is moved toward the base chuck 33 to clamp the bottle B between the two chucks during decoration thereof. Further depression of the foot treadle causes a control valve 39 to be actuated to operate a piston motor 40 (Fig. 1) and impart oscillatory movement in one direction to the stencil screen S while at the same time the base chuck 33 is rotated so that the bottle B will make tangential rolling line contact with the moving screen. During oscillation of the screen S, a squeegee S' forming part of a squeegee assembly 41 is maintained in contact with the screen along the line of contact between the screen and bottle. Upon completion of the decorating stroke, means is provided for elevating the squeegee out of contact with the screen to clear the pool of decorating enamel placed thereon. Upon release of the treadle, the head chuck 34 is movable away from the base chuck 33 to release the decorated bottle.

THE BOTTLE SUPPORTING ASSEMBLY

(a) The head chuck and base chuck mountings

Referring now to Figs. 1, 2, 6 and 7, the bottle supporting assembly comprises an elongated support 45 which is clamped as at 46 for axial adjustment on a tiltable cradle 47, the latter being pivoted as at 48 (Figs. 6 and 7) to a standard 49 bolted as at 50 to the table portion 31 of the carrier 30. A sector plate 51 depends from the cradle 47 and the lower edge 52 thereof cooperates with a clamping member 53 for clamping the plate 51 and consequently the cradle 47 in any desired adjusted position.

The head chuck 34 is carried at the outer end of a piston rod 55, the piston 56 for which is disposed in a cylinder 57 clamped as at 58 for axial adjustment on the support 45 adjacent one end thereof. A coil spring 59 normally urges the piston rod 55 to a retracted position. The other end of the support 45 terminates in a plate 60 (see also Fig. 3) to which there is secured a frame 61 having a cover plate 62 associated therewith. The base chuck 33 is provided with a shank 63 which is rotatably journaled in the plate 60 and from which there extends a stub shaft 64. A sprocket 65 is mounted on and keyed to the stub shaft 64 and forms one element of a train of driving mechanism which will be described presently and by means of which the base chuck is periodically rotated in opposite directions in order that the bottle B supported between the head and base chucks 34 and 33 respectively may make tangential rolling line contact with the oscillatable stencil screen S.

It is apparent that by virtue of the clamping means 58 the head chuck 34 may be adjusted toward and away from the base chuck 33 in order to accommodate bottles of different lengths. Also, the positions of the base and head chucks 33 and 34 may be adjusted in unison axially in order to bring the shoulder portions of the bottles B into accurate register with the sweep of the decorating portions of the screen S to properly locate the decorations on the bottles.

(b) The control valve for the head chuck

In order to periodically move the head chuck 33 from its retracted position against the action of the spring 59 and thus clamp a bottle B between the two chucks, means is provided for periodically supplying air under pressure to the cylinder 57 to impel the piston 56 therein for-

ward. Toward this end, the interior of the cylinder 57 communicates through a flexible conduit 66 with the control valve 37 (Fig. 4) through which compressed air is supplied from a compressed air tank 67 suitably mounted on the carrier 30 beneath the table portion 31.

The control valve 37 (Figs. 4, 17, 20 and 21) comprises a cylinder 70 which depends from the table portion 31 and which is formed with aligned ports 71 and 72 therein and an exhaust port 73. The port 71 communicates with the conduit 66 while the port 72 communicates through a conduit 74 with the compressed air tank 67. A piston valve member 75 disposed within the cylinder 70 is provided with an annular groove 76 and communicating longitudinal grooves 77 and 78 respectively, which grooves are adapted to establish communication between the exhaust port 73 and port 71 when the valve member 75 is extended as shown in Fig. 20 and to establish communication between the ports 71 and 72 when the valve member is elevated as shown in Fig. 21.

The valve member 75 is connected through a thrust link 80 (Fig. 4) to a lever 81 secured to a rock shaft 82 supported in brackets 83 suspended from the carrier 30. The rock shaft is connected through levers 84 to the foot treadle 38 and is adapted to be actuated thereby. A spring 85 serves to elevate the foot treadle 38 and maintain the valve 37 in the position shown in Fig. 20 wherein the cylinder 57 is exhausted to the atmosphere and the head chuck 34 is in its retracted position.

It is apparent that upon initial depression of the treadle 38, the valve 37, through the medium of the rock shaft 82, lever 81 and link 80, is moved to the position shown in Fig. 21 and air is supplied to the cylinder 57 to move the head chuck 34 to its bottle engaging position.

(c) Base chuck rotating instrumentalities

Referring now to Figs. 2 and 3 wherein the train of mechanism previously mentioned for rotating the base chuck 33 in opposite directions is shown, a bracket 90 suspended from the support 45 serves to rotatably support one end of an elongated spline shaft 91, the other end of which is rotatably journaled in the plate 60 and carries a sprocket 92. A chain 93 passing over the sprockets 92 and 65, having a tightening mechanism 94 associated therewith, serves to drive the base chuck 33 from the shaft 91.

The shaft 91 is adapted to be rotated in the opposite direction as periodically and toward this end a superstructure 95 secured to the table portion 31 of the carrier 30 serves to slidably support a horizontally reciprocable rack 96 which meshes with a gear 97 mounted on a shaft 98 (see also Fig. 6) rotatably journaled in the superstructure 95. A pair of bevel gears 99 and 100 connect the shafts 98 and 91. The rack 96 is adjustably secured as at 101 to a piston rod 102 and is axially adjustable with respect to the latter, the adjustable connection being provided in order to compensate for any arbitrary adjustment of the angularity of the article supporting assembly 32 to insure that the rack 96 will not become disengaged from the gear 97 during normal reciprocation of the former. A piston 103 mounted on the rod 102 is slidably disposed in a main operating cylinder 104 secured in the superstructure 95 and the piston is adapted to be reciprocated by the admission of compressed air through the control valve 39 alternately to the

opposite sides of the cylinder 104 in a manner subsequently to be described.

A pointer 105 (Figs. 2 and 3) secured to the frame 61 overlies the bottle B when supported in the chucks 33 and 34 and facilitates insertion of the bottle in the apparatus properly oriented for application of the decoration to the shoulder portions thereof on opposite sides of the usual mold seams occurring on the bottle.

10 THE STENCIL SCREEN ASSEMBLY

(a) The stencil screen mountings

Referring now to Figs. 1 and 2, a hollow standard 110 extends upwardly from the base portion 15 of the superstructure 95 and has secured thereto adjacent the top thereof a hollow horizontal arm 111 which in part overlies the bottle supporting assembly 32. The forward end of the arm 111 is provided with a web 112 and a removable cover 20 plate 113 providing a gear box or chamber 114. Extending vertically through the gear box 114 and journaled in bearings 115 therein is a tubular sleeve 116, the lower end of which depends from the arm 111 and has secured thereto an inverted U-shaped frame 117, the legs 118 of which have 25 slidably mounted therein vertically adjustable rack bars 119 (Fig. 4) that mesh with pinions 120 mounted on a shaft 121 extending across the frame. An adjusting screw 122 controls the elevation of the rack bars 119 while a tightening screw 123 locks the shaft 121 and consequently the rock bars 119 in any desired adjusted position. 30 A stencil screen frame 124 is suspended from the lower ends of the rack bars 119 and, upon manipulation of the screws 122 and 123 is adjustable to the proper height for cooperation of the screen S supported thereby with the tapered shoulder portion of the bottle B positioned between the chucks 33 and 34.

40 (b) *Instrumentalities for reciprocating the stencil screen.*

Still referring to Figs. 1 and 2, and in addition to Figs. 4, 12 and 13, a rack bar 130 is slidable in a guide 131 provided between the table portion 31 of the carrier 30 and the superstructure 95. The rack bar 130 meshes with a pinion 132 mounted on a vertical shaft 133 disposed within the standard 110. A bevel gear 134 at the upper end of the shaft 133 meshes with a similar bevel gear 135 mounted on the inner end of a shaft 136 mounted within the horizontal arm 111. The outer end of the shaft 136 carries a bevel gear 137 which meshes with a bevel gear 138 mounted on the tubular sleeve 116 within the gear box 114. Thus it will be seen that reciprocation of the rack bar 130 causes oscillation of the entire stencil screen assembly 35 about the axis of the tubular sleeve 116 and the amplitude of such oscillation is dependent upon the extent of reciprocation of the rack bar 130.

(c) *Instrumentalities for varying the oscillation of the stencil screen,*

65 Referring now to Figs. 2, 6, 8, 9, 10 and 11, the forward end of the rack bar 130 is connected as at 140 to a slidable bar 141 on which there is disposed a transversely extending channel member 142 providing a guideway 143. A hollow beam 144 (Figs. 2 and 11) is capable of oscillation about a vertical pin 145 and slidably carries therein a block 147 on which there is mounted a roller 148 riding in the guideway 143. The block 147 is adjustable in the beam 144 toward and away from the axis of the pin 145 by means of an adjusting

screw 150 and may be clamped in any desired adjusted position by means of a clamping screw 151 which actuates a wedge 152 within the beam 144. Thus it will be seen that the nearer the position of the block 147 to the axis of the pin 145, the smaller will be the extent of reciprocation of the rack 132 when the beam 144 is oscillated uniformly. A pointer 153 (Figs. 9 and 10) is secured to the block 147 and overlies a scale 154 on the beam 144 and facilitates proper adjustment of the parts for varying the amplitude of oscillation of the block 147 and consequently for varying the amplitude of reciprocation of the rack 130.

The block 147 has mounted thereon a roller 155 which rides in a guideway 156 provided by a channel member 157 secured to the underneath side of the reciprocable rack 96. It is apparent that driving communication is thus established from the piston 104, through the rack 96, adjusting mechanism just described, rack 132, and train of driving elements 132, 133, 134, etc. to the stencil screen assembly 35. 15 20

THE SQUEEGED ASSEMBLY

(a) *The squeegee assembly mountings*

Still referring to Fig. 2, a bracket 160 depends from the horizontal arm 111 and carries at its lower end a horizontal rock shaft 161 on which the squeegee assembly 41 per se is pivoted. The squeegee assembly 41 includes a slotted tubular member 162 or support having a bifurcated portion 163 pivoted to the rock shaft 161. A clamp 164 or squeegee holder support (see also Figs. 13 and 14) surrounds the member 162 and is adapted to be adjustably clamped in any desired axial position thereon by means of a clamping bolt 165. The squeegee holder support 164 is formed with a vertically extending recess 166 or guideway therein which is covered by a plate 167. A squeegee holder 168 is vertically adjustable in the recess 166 by means of an adjusting screw 169, a clamping nut 159 being provided for locking the holder in any desired adjusted position. The lower end of the holder 168 is bifurcated as at 170 and the squeegee S' is pivotally supported between the furcations of the holder by means of a spring pressed pin 171 which extends through a hole 172 formed in the squeegee S'. The pin 171 is retractable from the hole 172 to permit the squeegee S' to be readily removed from the holder and to permit substitution of squeegees.

(b) *Mechanism for elevating the squeegee at the end of each stroke of the stencil screen*

Returning to Fig. 3, a spring pressed plunger 175 extends through the tubular member 162 and is provided with a head 176 which is selectively receivable in one of a pair of notches 177 and 178 provided in a lifting member 179 pivoted to the rack shaft 161. A rod 181 extends through the sleeve 116 and is adjustably secured as at 182 to one end of a lever 183 which is pivoted as at 184 medially of its ends to a bracket 185 mounted on the arm 111. The other end of the lever 183 is connected to a link 186, the effective length of which may be adjusted by means of an adjustable coupling 187. The lower end of the link 186 is connected to a lever 188 which is pivoted medially of its ends to an extension 189 formed on a bracket 190 secured to the superstructure 95. A coil spring 194 normally urges the link 186 upwardly to tilt the lever 183 in such a manner that a downward impetus is applied to the squeegee S'. The other end of the lever 188 carries a cam roller 191

which bears against a reciprocable runway 192 or slide member which is formed as an extension of the rack bar 96. A pair of wedge-like members 193 or cams is adapted upon reciprocation 5 of the rack bar 96 to pass under the cam roller 191 as the stencil screen S approaches the limit of its stroke in either direction to actuate the train of mechanism just described leading from the roller 191 to the squeegee S' to elevate the 10 latter as the stencil screen S moves to its limiting positions.

(c) *Mechanism for rendering the squeegee inoperative*

15 The spring pressed plunger 175 is formed with a ring 195 on the free end thereof by means of which the plunger may be retracted to withdraw the plunger head 176 from the notch 177. When this is done, the entire squeegee assembly 41 may 20 be tilted upwardly and the plunger 175 released to allow the head 176 to enter the notch 178 and maintain the assembly in such a position that the stroke of the link 186 is of insufficient amplitude to cause the squeegee to contact the 25 screen.

THE CONTROL VALVE FOR THE MAIN OPERATING CYLINDER

30 Referring now to Figs. 16, 17, 18, 19 and 22, the control valve 37 is connected by means of a link 200 to a lever 201 (Fig. 4) mounted on the rock shaft 82 and thus the valve 37 is operable from the foot treadle 38. Conduits 203 and 204 35 connect the valve 37 with opposite ends of the cylinder 104 while a conduit 205 leading from the compressed air tank 67 establishes communication through branch conduits 206 and 207 with the valve 37.

40 The valve 37 is substantially identical in construction with the control valve for the main operating cylinder of the structure shown and described in detail in a copending application for United States Letters Patent filed by J. E. McLaughlin and A. S. Jackson, Serial Number 45 231,888, filed September 27, 1938, for Stenciling apparatus, and reference may be had to said application for a full disclosure thereof. It is deemed sufficient to state that the conduits 203, 204, 206 and 207 are so connected to the valve 50 37 that upon depression of the foot treadle 38 slightly beyond an initial movement thereof, the valve becomes operative to drive the piston 103 in the main operating cylinder 104 in one direction by admitting compressed air to one end of the cylinder. Upon the next succeeding operation of the treadle mechanism, the valve 37 becomes 55 operative to drive the piston in the opposite direction. In this manner the stencil screen and bottle are actuated in unison in the manner previously described so that they make tangential 60 rolling line contact with each other at each decorating stroke of the screen. However, the decorative stroke of the screen on alternate bottles is performed in opposite directions.

65 From the above description it is thought that the versatility of adjustment of the stenciling apparatus to accommodate all manner of bottles or other ware, as well as the many advantages thereof, will be fully understood without further elaboration. While the invention has been illustrated and described in connection with an apparatus for decorating the curved tapered shoulder portions of the bottles, it is obvious that by slight modification thereof, the apparatus may 70 serve to decorate the cylindrical sides of bottles 75

or other articles. In the appended claims, the term "reciprocation" is intended to mean a to-and-fro motion of the stencil screen whether this motion be in a straight path or in a curved one. Other modifications may be resorted to within 5 the spirit of the appended claims.

We claim:

1. In an apparatus for decorating the curved surfaces of articles by a stenciling process, a horizontally reciprocable stencil screen, a squeegee support positioned above the screen, a squeegee holder mounted on the support, said holder having a bifurcated lower end, a retractable pin projecting through one of the furcations of said lower end and engaging the other 10 furcation thereof and bridging the said furcations, a squeegee pivotally suspended from the pin, and spring means normally maintaining the pin in position against dislodgment.

2. In an apparatus for decorating the curved 20 surfaces of articles by a stenciling process, a horizontally reciprocable stencil screen, a substantially horizontally disposed squeegee support positioned above the screen, a clamp mounted for axial adjustment on the horizontal support, 25 there being a vertical guideway in the clamp, a squeegee holder disposed in the guideway and vertically movable therein, means for adjusting the position of the holder in the guideway, clamping means for releasably securing the holder in the guideway in any desired adjusted position, and a squeegee pivotally suspended from the lower end of the holder.

3. In an apparatus for decorating the curved 30 surfaces of articles by a stenciling process, a horizontally reciprocable stencil screen, a horizontally disposed squeegee support positioned above the screen, a clamp mounted for axial adjustment on the horizontal support, there being a vertical guideway in the clamp, a squeegee 35 holder disposed in the guideway and vertically movable therein, means for adjusting the position of the holder in the guideway, said holder having a bifurcated lower end, a retractable pin 40 projecting through one of the furcations of said lower end and engaging the other furcation thereof and bridging the furcations, a squeegee pivotally suspended from the pin, and spring means normally maintaining the pin in position against dislodgment.

4. In an apparatus for decorating the curved 50 surfaces of articles by a stenciling process, a horizontally reciprocable stencil screen, a horizontally disposed rock shaft disposed above the screen, a lifting member pivoted to the shaft, 55 means for swinging the lifting member through a limited arc, a squeegee support pivoted to the shaft and capable of swinging movement relative to the lifting member, a squeegee holder secured to the support, a squeegee carried by the 60 holder, and means releasably locking the support to the lifting member in a plurality of adjusted positions.

5. In an apparatus for decorating the curved 65 surfaces of articles by a stenciling process, a horizontally reciprocable stencil screen, a horizontally disposed rock shaft disposed above the screen, a lifting member pivoted to the shaft, 70 means for swinging the lifting member through a limited arc, a squeegee support pivoted to the shaft and capable of swinging movement relative to the lifting member, there being a pair of notches in the lifting member at different elevations therein, a retractable plunger carried by the 75

support and selectively receivable in said notches, and a squeegee mounted on the support.

6. In an apparatus for decorating the curved surfaces of articles, a horizontally reciprocable stencil screen, a horizontally disposed rock shaft disposed above the screen, a lifting member pivoted to the shaft, said lifting member being capable of swinging movement on the shaft through a limited arc from a lowered position to an elevated position and vice versa, means for reciprocating the screen, cam means for elevating the lifting member as the screen approaches the end of its stroke in either direction, a squeegee support pivoted to the shaft, means connecting the support to the lifting member, and a squeegee mounted on the support.

7. In an apparatus for decorating the curved surfaces of articles, a horizontally reciprocable stencil screen, a horizontally disposed rock shaft disposed above the screen, a lifting member pivoted to the shaft, said lifting member being capable of swinging movement on the shaft through a limited arc from a lowered position to an elevated position and vice versa, means for reciprocating the screen, cam means for elevating the lifting member as the screen approaches the end of its stroke in either direction, a squeegee support pivoted to the shaft, means releasably locking the support to the lifting member in a plurality of adjusted positions, and a squeegee mounted on the support.

8. In an apparatus for decorating the curved surfaces of articles, a horizontally reciprocable stencil screen, a horizontally disposed rock shaft disposed above the screen, a lifting member pivoted to the shaft, said lifting member being capable of swinging movement on the shaft through a limited arc from a lowered position to an elevated position and vice versa, a piston motor including a reciprocable piston for actuating the screen, a vertically movable cam member for elevating the lifting member, a slide member connected to the piston for reciprocation therewith, and a pair of cams mounted on the slide member and alternately movable upon movement of the slide member into engagement with the cam member to elevate the latter.

9. In an apparatus for decorating the tapered shoulder portions of bottles and like articles by a stenciling process, a support, a stencil screen mounted for oscillation in a horizontal plane above the support, a standard on the support beneath the screen, a tiltable cradle pivoted to the standard in a plurality of adjusted positions, a bottle support mounted on the cradle, a rotatable chuck on the bottle support, means for adjusting the position of the bottle support on the cradle axially of the chuck, a splined shaft rotatably mounted on the bottle support, means connecting the chuck and shaft in driving relationship, a gear slidable on the shaft, a driving gear meshing with the other gear, and means for rotating the driving gear alternately in opposite directions.

10. In an apparatus for decorating the tapered shoulder portions of bottles and like articles by a stenciling process, a support, a stencil screen mounted for oscillation in a horizontal plane above the support, a standard on the support

beneath the screen, a tiltable cradle pivoted to the standard, means for clamping the cradle to the standard in a plurality of adjusted positions, a bottle support mounted on the cradle, a rotatable chuck on the bottle support, means for adjusting the position of the bottle support on the cradle axially of the chuck, a splined shaft rotatably mounted on the bottle support, means connecting the chuck and shaft in driving relationship, a gear slidable on the shaft, a driving gear meshing with the other gear, a reciprocable rack, a piston motor for causing reciprocation of the rack, means translating reciprocation of the rack to oscillation of the screen, and means translating reciprocation of the rack to alternate rotation of the driving gear in opposite directions.

11. In an apparatus for decorating the curved surfaces of articles by a stenciling process, a support, a stencil screen mounted for reciprocation in a horizontal plane above the support, a rotatable bottle supporting chuck disposed beneath the screen, a reciprocable rack, means for reciprocating the rack, means translating reciprocal motion of the rack to alternate rotation of the chuck, a second reciprocable rack, an oscillatable beam mounted on the support for swinging movement about a vertical axis, means translating reciprocation of the first rack to oscillation of the beam, means translating oscillation of the beam to reciprocation of the second rack, and means translating oscillation of the second rack to reciprocation of the screen.

12. In an apparatus for decorating the curved surfaces of articles by a stenciling process, a support, a stencil screen mounted for oscillation in a horizontal plane above the support, a rotatable bottle supporting chuck disposed beneath the screen, a reciprocable rack, means for reciprocating the rack, means translating reciprocal motion of the rack to alternate rotation of the chuck, a second reciprocable rack, an oscillatable beam mounted on the support for swinging movement about a horizontal axis, a cam member adjustably mounted on the beam for movement toward and away from the axis of oscillation thereof, a cam groove on the second rack in which the cam member travels to translate oscillation of the beam to reciprocation of the second rack, and means translating reciprocation of the second rack to oscillation of the screen.

13. In an apparatus for decorating the curved surfaces of articles by a stenciling process, a support, a stencil screen mounted for oscillation in a horizontal plane above the support, a rotatable bottle supporting chuck disposed beneath the screen, a reciprocable rack, means for reciprocating the rack, means translating reciprocal motion of the rack to alternate rotation of the chuck in opposite directions, a second reciprocable rack, an oscillatable beam mounted on the support for swinging movement about a horizontal axis, a cam member adjustably mounted on the beam for movement toward and away from the center of oscillation thereof, means connecting the cam member and second rack to effect reciprocation of the latter, and means translating reciprocation of the second rack to oscillation of the screen.

ALBERT S. JACKSON.
